UNITED STATES PATENT OFFICE.

ADOLPH G. KAUFMAN, OF NEW YORK, N. Y.

VAPORIZER AND HOLDER.

1,342,446.

Specification of Letters Patent. Patented June 8, 1920.

Application filed July 15, 1919. Serial No. 310,930.

To all whom it may concern:

Be it known that I, ADOLPH G. KAUFMAN, a citizen of the United States, residing at New York, in the county and State 5 of New York, have invented new and useful Improvements in Vaporizers and Holders, of which the following is a specification.

This invention relates to lamps, and especially to that class of lamps where the volatile fluid, as kerosene or gasolene, is vaporized, and burned in connection with an incandescent mantle, or mantles; and the object of this invention is to provide a vaporizer and holder for a lamp of this 10 kind which will be simple to manufacture and efficient in use.

The invention is illustrated in the accompanying drawing, in which—

Figure 1, is an elevation, partly in section, of a vaporizer holder constructed in accordance with my invention, and an elevation of a part of a vaporizer I may employ;

Fig. 2, is a view of a modified form of holder; and

Fig. 3, is a view of another modified form of construction.

In the drawing similar numerals of reference refer to the same parts in each of the 30 views.

In practice I provide the vaporizing tube 4, with a lower end 5, adapted to be seated in the socket 6, of the part 7 in a manner to form a tight connection. This end 5 is 35 adapted to be forced down into engagement with the seat 6 with the nut 8 slidably and rotatably mounted on the vaporizing tube 4, and adapted to bear against the top 9 of the end, or head 5 of the vaporizing tube so 40 that in screwing the screw-threaded shank 10 of the nut 8 into the screw-threaded part 7, the head will be forced downward into close contact with the seat, as will be understood.

45 As shown in Fig. 1, the nut 8 can be rotated by engaging the part below the pre-heating cup 11; or the preheating cup may be fastened on the shank 12 integral with the nut 8 so that the cup may be used as a 50 tool to rotate the nut, as will be understood.

As shown in Fig. 1, the vaporizing tube 4 is of special construction in that the tube is provided with a curved portion 13 located above the cup 11. I do not consider the 55 curl in the vaporizing tube as new, but do consider it new to locate this curl above the

preheating cup so that a flame from the preheating cup will act directly on the coil, or curl in the vaporizing tube, or a match can be held to the coil, or curl, or a match 60 can be laid in the preheating cup without putting any alcohol in the same and the flame of the match will ascend to the coil to generate sufficient gas to start the lamp.

It will be understood that I do not limit 65 myself to the kind of vaporizing tube shown in Fig. 1, as the way of holding the vaporizing tube is important for use with any kind of vaporizer.

In Fig. 2 I have shown a modified form 70 of construction in that the nut 8' does not carry a shank, as 12; but the cup 11' has a pocket 14 formed therein adapted to fit over the "hex" nut 8. When this construction is used it is evident that the cup 11' 75 will act as a tool to rotate the nut 8', to screw the parts down to draw the head 5' into close contact with the seat 6' in the part 7'.

In Fig. 3 the cup 11^a has a central orifice 80 15 adapted to fit over the nut 8' to rotate the same. The flange 16 will prevent the alcohol leaving the cup when placed in the same.

In the construction shown in Fig. 2 the 85 vaporizing tube 4' may be the ordinary vaporizing tube, or may be the same kind of vaporizing tube shown in Fig. 1. In Fig. 3, the vaporizing tube 4^a may also be the same as described with reference to this part in 90 Fig. 2. In Fig. 3 the parts 5^a, 6^a, and 7^a are the same as described with reference to the other figures.

If the cup 11 in Fig. 1 is provided with a flange 17, it is evident that the cup may rotate on the hub, or shank 12, of the nut 8, in which case the nut would have to be operated with a wrench on the part below the cup. In any event the cup would be effective for a match receptacle below the coil, 100 or curl in the vaporizing tube; and the flame from the alcohol in the vaporizing tube would also be effective in generating gas since the coil, or curl is located directly above the cup.

105 It will thus be seen that I have provided a vaporizer and holder that is simple in construction and efficient in use.

I claim:

1. In a lamp, a vaporizing tube having a 110 head with a beveled end, a nut adapted to force said head into a tight connection with

a seat whereby fluid may be fed to the vaporizer without leakage, and a preheating cup adapted to operate said nut, said vaporizer having a coil, or curl formed therein.

2. The herein described vaporizer and holder comprising a vaporizing tube having a head with a beveled end, a part leading to the reservoir having a seat corresponding with said beveled end, a nut rotatably mounted on the vaporizer and adapted to

force said head into engagement with said seat, and a preheating cup adapted to rotate said nut, for the purpose set forth.

3. In a lamp, a vaporizing tube, a nut 15 adapted to make a close connection between the reservoir and said tube, and a preheating cup adapted to rotate said nut, for the purpose set forth.

Dated 14th day of July, 1919.

ADOLPH G. KAUFMAN.
